UNITED STATES PATENT OFFICE.

WILLIAM L. JAMESON, OF DENVER, COLORADO.

STEAM-SEPARATOR.

SPECIFICATION forming part of Letters Patent No. 696,446, dated April 1, 1902.

Application filed November 19, 1900. Renewed September 10, 1901. Serial No. 74,903. (No model.)

To all whom it may concern:

Be it known that I, WILLIAM L. JAMESON, a citizen of the United States of America, residing in Denver, county of Arapahoe, and State 5 of Colorado, have invented a certain new and useful Device or Apparatus for Separating Steam from Water, of which the following is a specification.

My invention relates to a device or apparatus for use in boilers to produce a rapid separation of the steam from the water during the heating of the water. I accomplish this by stirring and maintaining a constant circulation of water in all parts of a boiler, whereby 15 all of the water is brought into contact with the heating-surfaces of a boiler. The movement of the device or apparatus in the boiler also prevents accumulation of sediment or scale in the boiler and on the flues.

20 I will describe a device or apparatus embodying my invention and several modifications thereof and then point out the novel features thereof in the claims.

In the accompanying drawings, Figure 1 is 25 a longitudinal sectional view of a tubular boiler equipped with a device or apparatus embodying my invention, parts of the said device being shown in section. Fig. 2 is a cross-sectional view of Fig. 1. Fig. 3 is a detail view illustrating a modification of my device. Fig. 4 is a detail view illustrating a further modification of my device. Fig. 5 is a detail view showing a way of securing straight agitator-blades to the device.

30 35 Similar letters of reference designate corresponding parts in all of the figures.

Referring now more particularly to Figs. 1 and 2, A represents a boiler, A' a steam-dome therefor, and A² the heating flues or tubes, 40 which, as shown in Figs. 1 and 2, are regularly arranged in vertical and horizontal rows.

B represents a frame extending longitudinally of the boiler A and arranged in the plane of the vertical diameter of the boiler. 45 The frame comprises a top longitudinal member b, a bottom longitudinal member b', vertical sectional members b², and inclined braces b³, intermediate of the top, bottom, and vertical members. The sections of the vertical 50 members are separately secured to the top and bottom members of the frame, the purpose of which being to enable agitator bars

or blades to be easily secured in position in assembling the frame within a boiler. Each vertical section is provided with notches or 55 recesses b⁴ in their adjacent faces in which the agitator bars or blades are held. The several parts of the frame are detachably put together, thereby enabling the several parts thereof to be conveniently introduced in the 60 boiler and there assembled.

C represents the agitator bars or blades. These bars or blades are arranged transversely relatively to the frame. The top and bottom edges of the bars or blades are recessed or cut away at intervals to conform to the contour of the tubes or flues B. Each bar or blade C is so formed as to have a clearance between it and adjacent tubes, an object being to obviate wear of the tubes by the 70 bars or blades C when the frame B is reciprocated. A further object of the clearance between the bar or blades C and the tubes is to permit of water circulating between the bars or blades and the tubes. In the present instance this clearance is provided by having each recess or cut-away portion c in the bars or blades C sufficiently deep.

The frame B is supported in position within the boiler by means of cross-pieces D D', two 80 pieces D being arranged and secured on the top horizontal row of tubes B and two pieces D' being secured to the lowermost horizontal row of tubes B. The pieces D and D' are fixedly secured in place by any desired means— 85 as, for example, by U-clamps d. The bars D D' are each provided with a recess, in which the top and bottom longitudinal members b b' of the frame B slide as the frame B is reciprocated. The reciprocation of the frame is accomplished by means of a crank D², operated 90 from an engine D³, which is supplied with steam through a conduit d' from the steam-dome A'.

Secured to the bottom longitudinal member 95 b' are a number of blades E and brushes E', which conform to the inner contour of the body. In some instances a blade or brush may be secured to the vertical members of the frame. Each blade and brush has a hinged connection e with its support, preferably of such a character as to permit of the blade or brush dragging when the frame B is reciprocated in one direction. A purpose of these

blades and brushes is to keep in circulation the water at the lower part of the boiler. A further purpose of the blades and brushes is to move any sediment or other matter deposited on the bottom of the boiler toward a valved blow-off pipe E². The blades and brushes are so arranged as to have their planes of movement overlap. The brushes E' are also secured to the frame B in such position as that their planes of movement will include the rivets, patches, braces, and seams at the bottom of the boiler.

The reciprocation of the frame and agitator bars, brushes, and scrapers will prevent scales forming on the tubes or flues and the interior lower surface of the boiler. The agitator bars, brushes, and blades will also remove any scale or sediment that may have been formed. All scale may be removed from the tubes or flues by supplying the agitator bars or blades with removable scraping edges. After all the scale has been removed these edges are removed.

In Fig. 3 I have shown the agitator bars or blades C as consisting of straight and comparatively thin bars, arranged between adjacent horizontal rows of tubes and clamped between the vertical sectional members. (See Fig. 5.)

In Fig. 4 I have shown vertical straight agitator bars or blades C' arranged between adjacent vertical rows of tubes and as being carried by the frame B. These vertical bars are secured in any desired manner to transversely arranged bars C², carried by the upper longitudinal member of the frame B. These vertical bars may be used separately or in connection with the horizontal straight bars C. In this event the vertical and horizontal bars are alternated throughout the length of the frame.

In place of the horizontal and vertical straight bars I may use chains or cables. If chains or cables are used, they are held rigid, so that in the reciprocation of the frame they will not come in contact with the tubes or flues B.

The frame B and the agitator bars or blades carried thereby are adapted to be reciprocated constantly. This continued movement causes a rapid ebullition of steam from the water.

A constant circulation of water is also maintained, whereby a uniform heating of the water in all parts of the boiler is obtained.

What I claim as my invention, and desire to secure by Letters Patent, is—

1. The combination with a tubular boiler of a device for separating steam from the water being heated in the said boiler, said device comprising a frame having means for re-

ciprocating it, means carried by said frame which are arranged between adjacent tubes of the boiler but out of contact with the tubes, and other means also carried by the frame for circulating the water at the bottom of the boiler and for moving sediment from the bottom of the boiler to the blow-off pipe thereof.

2. The combination with a tubular boiler of a device for separating steam from the water being heated in said boiler, said device comprising a frame having means for reciprocating it longitudinally of the boiler, agitator-blades, carried by said frame and arranged between adjacent tubes but out of contact with said tubes, said agitator-blades being so arranged on said frame relatively to each other as to have their planes of movement overlap.

3. In a device for releasing steam from water, the combination of a frame comprising top, bottom and vertical sectional members and inclined braces and transversely arranged agitator-blades secured between said vertical sectional members.

4. In a device for releasing steam from water, the combination of a frame comprising top, bottom and vertical members, agitator-blades, carried by said frame, and means for reciprocating said frame, substantially as described.

5. In combination with a tubular boiler, a frame arranged longitudinally thereof, cross-bars fastened to the tubes of said boiler for supporting said frame, means for reciprocating said frame, and agitator-blades carried by frame and disposed between the tubes of the boiler.

6. In combination with the tubular boiler, a frame arranged longitudinally of the boiler and having means connected therewith for reciprocating it, said frame comprising top, bottom and vertical members detachably secured together, and agitator-blades detachably carried by said frame and disposed between the tubes of the boiler.

7. In combination with a tubular boiler, a frame provided within said boiler and with means for reciprocating it therein, and devices carried by said frame which are disposed among the tubes of the boiler and out of contact therewith for stirring and circulating the water in the said boiler.

In testimony whereof I have signed my name to this specification in the presence of two subscribing witnesses.

WILLIAM L. JAMESON.
